UNITED STATES PATENT OFFICE.

DAVID J. ETRY, OF LOUISVILLE, KENTUCKY.

APPARATUS FOR CURING TOBACCO ARTIFICIALLY.

SPECIFICATION forming part of Letters Patent No. 655,214, dated August 7, 1900.

Application filed August 16, 1899. Serial No. 727,391. (No model.)

To all whom it may concern:

Be it known that I, DAVID J. ETRY, a citizen of the United States, residing at Louisville, in the county of Jefferson and State of Kentucky, have invented certain new and useful Improvements in Apparatus for Curing Tobacco Artificially; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to certain improvements in the means heretofore proposed for artificially curing tobacco, which contemplate the subjection of the tobacco successively to the actions of heating and refrigerating temperatures artificially produced, or, looking at the invention from another point of view, to improvements in the previous proposals of curing tobacco artificially which spray the same with steam while it is contained in an air-tight receptacle. These previous proposals—namely, those which depend for the curing of the tobacco upon inducing a rapid and yet controllable sweating of the same by means of steam sprayed thereon while in a steam-tight receptacle and subsequently permitting the tobacco to dry naturally and those wherein the curing consists in successively subjecting the tobacco to heating and refrigerating temperatures—have each been defective in some essential particular and have not proved successful in practice. This is likewise true of a previous proposal, which consists in steaming, refrigerating, and drying the tobacco, combined with intermediate steps of treating the tobacco with certain acids.

In treating tobacco by the means herein-after described the tobacco to be cured is not only subjected to the action of heating and refrigerating agents, which alone are not efficacious in developing the aroma, taste, and appearances characteristic of the well-cured leaf, and is not alone sprayed and dried, but it is subjected to a combination of these steps—that is to say, it is first sprayed and refrigerated and then heated and dried—and these several steps are practiced while the tobacco

is hung up in "hands" on racks arranged in an air-tight chamber and under the following further peculiar conditions, namely: Steam is utilized, as heretofore proposed, to produce the spray; but as it is not deemed desirable to spray the tobacco with live steam the temperature of the chamber within which the tobacco undergoing treatment is hung is lowered during the spraying step of the treatment, and the refrigerating step of the treatment bears such relation to the spraying step thereof that the moisture absorbed by and developed in the leaves during the spraying step becomes frozen throughout the leaves. By carrying out the first step of the treatment under a condition of low temperature and by refrigerating the moisture taken up by the leaves during said first step of the treatment incomparably-better results are produced than when the tobacco is sprayed with live steam or refrigerated without being previously moistened. After the leaf has been moistened and frozen it is subjected to a high temperature, which dries it and coacts with the freezing temperature in imparting the condition of maturity thereto, and at certain times in the treatment the tobacco is subjected to the action of a current of air, with which the chamber or apartment is supplied, and the disagreeable odors and gases developed during the earlier stages of the treatment are withdrawn from the apartment. These several steps of the treatment are carried out in the one chamber and without necessitating handling of the leaf between the steps.

The best agent known for carrying out the refrigerating step of the treatment is a circulating column of chilled brine, and the best agent known to me for carrying out the other step of the treatment is steam. By treating the tobacco in a chamber which is as nearly air-tight as possible the leaf receives fully the benefits of the several temperatures produced by the heating and refrigerating agents employed, as said temperatures will be uninfluenced by surrounding atmospheric conditions, and in addition to said advantages it is advantageous in that certain constituents of the tobacco which are freed therefrom when the tobacco is moistened and when it is subjected to a rapid increase in its temperature to a high degree are not wholly lost to the

tobacco, but remain in the chamber and are enabled to give or assist in giving a characteristic aroma to the tobacco.

The apparatus shown in the accompanying drawings is not only constructed to utilize steam and a circulating column of chilled brine in carrying out the several steps of spraying, refrigerating, and heating and drying the tobacco and to enable said steps to be carried out successively in an air-tight chamber, within which the tobacco is hung up in hands, and without requiring handling of the tobacco between the steps of the treatment or its removal from the chamber during its entire period of treatment, but is still further advantageous in that pipes through which the heating agent flows are utilized for the chilling agents instead of providing separate pipes for the several agents. A principal aim in constructing the apparatus has been to produce the best possible results and with the fewest pipes and connections, thus obtaining the combined advantages of increased efficiency and simplicity.

25 The invention consists, generally stated, in certain novel features in the construction of the apparatus, substantially as hereinafter described, and particularly pointed out in the subjoined claims.

30 In the accompanying drawings, illustrating the invention, Figure 1 is a horizontal plan view of the apparatus, taken on the line xx of Fig. 2. Fig. 2 is a vertical sectional view of the apparatus on the line yy of Fig. 1. In both of said figures a fan for inducing a current of air in the apartment is shown. Fig. 3 is a detail perspective view of the system of pipes for the several agents similar to that shown in the previous figures, except that the 35 fan is dispensed with and compressed air is utilized instead thereof. Fig. 4 is a detail front view of the door of the chamber or apartment within which the tobacco is hung while undergoing the treatment, and Fig. 5 is a vertical section of said door.

45 The same letters and numerals of reference designate the same parts in the several views.

I have, as above stated, found that important advantages result when the tobacco undergoing treatment is hung up in hands within an air-tight chamber during the entire period of treatment. To this end I have shown herein a special construction of chamber or room A for the tobacco, which will be air-tight and uninfluenced by surrounding atmospheric conditions. Said chamber or apartment A preferably consists of an inner box-like structure 1 and an outer similar structure 2, relatively arranged and of such sizes as to provide a closed space 3 between them, which may constitute a dead-air space or be filled with a suitable non-conducting material, whichever is preferred. This apartment is provided with an air-tight door B, hinged 60 to afford access to its interior, and said door must be an air-tight one. The one shown best in Figs. 4 and 5 of the drawings consists of

an outer layer of tongue-and-grooved boards 4, a layer of boards 5, set to provide intervening dead-air spaces 6 between inner edges, 70 next a layer of closely-set tongue-and-grooved boards 7, then an upper and a lower board 8, arranged to provide a space for a filling 9 of magnesia, and, finally, an innermost layer of closely-set boards 10. These layers are arranged with the surface of one against the surface or surfaces of its neighbor or neighbors and successively decrease in area from the outer one inward, as shown. The space provided in the apartment A for the door will 80 of course have a jamb constructed to correspond with the edges of the door.

Other constructions of apartments than that above described may be employed without departing from the spirit of the invention. 85

In order that the temperature of the inner apartment may be observed at all times, the door is provided with a thermometer 11, as shown in Figs. 2 and 4.

Supported within the apartment A upon 90 cleats 12 or in any other suitable manner is a series of strips 13, which are arranged to provide racks from which the tobacco undergoing treatment depends in hands.

Leading from a suitable source of chilled-brine supply to one branch of a hollow cross or coupling 14 is a brine-pipe 15, having a valve 16, and leading into another branch of said coupling from a suitable source of compressed-air supply is an air-supply pipe 17, 100 having a valve 18, and leading into a third branch of said coupling from a steam-generator is a steam-supply pipe 19, having a valve 20. The particular means for refrigerating the brine and forcing it through the pipes 105 form no essential part of this invention, and as such means are well known in the art of refrigeration it is not deemed necessary to show them herein. A suitable means for the purpose consists of a brine-tank having there-in a coil of pipe through which circulates ammonia from a compressor, the gas of which acts to chill the brine. Said brine-tank is also connected with a steam-pump which forces the refrigerated brine from the tank and 110 through the pipes provided for its circulation. The steam-generator need not be shown, as it may be of conventional form, which likewise is true of the air-compressing apparatus. Leading from the fourth branch of the coupling 14 is a coil of pipe 21, which is located near the top of the box 1 and is common to the heating and refrigerating agents used in carrying out the treatment. This pipe leads to a T-coupling 22, from one branch of which 115 a steam-pipe 23 extends downward to near the bottom of the apartment, and from another branch of which a pipe 25 leads back to the source of refrigerated-brine supply. The steam-pipe 23 has a valve 24 adjacent to 120 said T-coupling, and the brine-return pipe 25 has a valve 26. Connected with the lower portion of the down-pipe 23 by a T-coupling 125 27 is a pipe 28, which is arranged near the

bottom of the box 1 and has a valve 29. Said pipe 28 may terminate in the atmosphere or may end in well-known means for returning condensed steam to the generator, whichever 5 is preferred. The steam-supply pipe 19, at a place forward of the valve 20 therein, is tapped by a pipe 30, which leads therefrom to the steam-pipe 23 and communicates with the latter at a place after that at which the valve 24 10 is located. Said pipe 30 is provided with a valve 31. From the T-coupling 27 leads downward a pipe 30^a, having a valve 31^a. This pipe 30^a communicates with a pipe 32, which is located, preferably, immediately above the 15 floor of the box or apartment A and has one end closed by a cap 33 and its upper surface formed with a number of perforations 34, which point in different directions and through which the tobacco is sprayed with 20 moisture. This connection of the spray-pipe with the steam-pipe permits the spray and the refrigerant to be used simultaneously. It is within the scope of the invention to connect the spray-pipe with the steam-supply pipe 25 by means which does not include the down-pipe 23.

The first step in the treatment of the tobacco by means of this apparatus is the spraying step conducted by steam under a condition 30 of low temperature which develops moistening properties thereof. In carrying out this step valves 16 and 26 are opened for the circulation of the refrigerant and valves 31 and 31^a opened for the supply of steam for 35 spraying purposes. It will be evident that the steam will now flow from pipe 19 through pipes 30 23 30^a and spray-pipe 32 in the order named and that brine will circulate through pipes 15, 21, and 25 and back to the 40 brine-tank. It may be that the tobacco will have been sufficiently sprayed before it has been subjected to a freezing temperature the time desired or required for the latter, and in such event valves 31 and 31^a are closed to 45 shut off steam, and the other valves, 16 and 26, are left open to continue the refrigerating period. It will be observed that the moisture absorbed by and developed in the tobacco during the spraying period is frozen during 50 the refrigerating period. When the tobacco has been sufficiently refrigerated, the brine-forcing means is stopped and no more brine enters the pipes, but pipe 21, with other pipes, remains filled with brine. As said pipe 21 55 forms part of the system through which steam flows in the heating step of the system, it is for many reasons deemed desirable to expel the brine from said pipe before steam is turned on for the next step of the treatment. To 60 this end valve 18 is opened and all the other valves, except 26, are closed, which causes air under pressure to rush through pipes 21 and 25 and force the brine out from the same and back to the brine-tank for reuse. Com- 65 pressed air is the preferred agent for this purpose, as it leaves pipe 21 wholly free of any fluid which would interfere with the free

circulation of steam and does not dilute the brine, but other agents may be employed without departing from the spirit of the invention. When pipe 21 has been thus freed from brine, valves 20, 24, and 29 are opened and all other valves are closed, thus causing steam to flow through pipes 19, 21, 23, and 28 and carry out the heating and drying step 70 of the treatment. It may be necessary or desirable to subject the tobacco to the action of an air current or currents during certain periods of treatment, and it is especially desirable to withdraw from the apartment gases 80 or odors that may arise during the earlier stages of the treatment. For these purposes a fan 34 may be utilized, as indicated in Figs. 1 and 2, or the use of compressed air may be resorted to, as shown in Fig. 3, under conditions which will permit them to expel said gases or odors when necessary. If the fan is employed, it may be of any suitable construction and driven by any suitable power, and it may be located within the apartment 90 or chamber, as shown in the drawings, or outside the same and suitably connected therewith without departing from the spirit of the invention. If compressed air is preferred, it will of course be obtained from the reservoir, 95 which holds the supply for driving brine from the pipes 21 and 25, and will be delivered into the apartment or chamber in any suitable manner—as, for instance, through the perforated pipe 35, which is connected with the 100 air-supply pipe 17 by a valved pipe or coupling 36.

The steps of treatment hereinabove described may be repeated as often as deemed necessary to bring the tobacco to the required 105 degree of maturity. It will be observed that during the entire period of treatment the tobacco remains in the apartment A, instead of being partially treated in one apartment and then removed to another apartment or to 110 other apartments for another portion or portions of the treatment.

While the valves which control the circulation of the various agents are shown as located within the apartment A, they may, if 115 desired, be outside the apartment, so as to be accessible without having to enter the latter.

It will be noted that in the apparatus described the refrigerating agent circulates through pipes located only near the ceiling 120 of the apartment. This is believed to be sufficient to cause all the tobacco to be uniformly refrigerated, especially when circulating refrigerated brine is used as the refrigerant. It will also be seen that the sprayed 125 steam ascends from the bottom of the apartment, which is evidently the best location for the spray-pipe. It is believed that the one spray-pipe will be ample to cause all the tobacco to be rapidly and thoroughly moistened, 130 especially when said pipe is, as shown, located near the center of the floor of the apartment and has its perforations directed to throw the spray toward various points in the apartment.

Furthermore, it will be observed that the steam for heating and drying purposes flows through pipes located at both the top and bottom of the apartment, whereby uniform heating and drying of the tobacco is more rapidly and efficiently accomplished than if the pipes therefor were located solely at the top or at the bottom of the apartment, and, finally, it will be observed that the construction of the system of pipes is such as to eliminate or dispense with many pipes and connections which would be required if a separate system were provided for each agent, as heretofore. This construction is thus advantageous in that it 10 provides means having the fewest possible pipes and connections by which the tobacco may be efficiently treated by the several agents described and without removal of the tobacco from the apartment until it has been 15 treated by all the agents; but, notwithstanding that I believe the specific construction described is the best adapted to attain fully the objects of the invention, many changes may be made without departing from the 20 spirit of the invention.

I desire to say that it is new in this art, as far as I am aware, to provide means by which the treatment of the tobacco, including saturation, refrigeration, and heating, is carried on in one apartment, and especially is it new to so construct the apparatus as that the several agents employed will flow through pipes common to them. It is also new in this art, as far as I am aware, to provide an apartment or receptacle for containing tobacco to be cured with pipes connected with sources of steam-supply and cold-supply, respectively, and with the connections such that the two (steam and cold) may be supplied to 30 the apartment at once as well as be supplied thereto at different times. These features of construction are important in producing a better result than heretofore attained, in reducing the number of pipes and connections 35 heretofore required, and in eliminating the labor and loss of time incident to the handling of the tobacco between the steps of the treatment, as well as in preventing the tobacco from being injuriously affected by atmospheric influences, to which it is subject if it is removed from the steaming-chamber 40 to another chamber between the spraying and refrigerating steps.

In order to assure that the apartment or 45 chamber A shall be steam or air tight, it will be desirable to provide the pipes at the places where they enter said apartment or chamber with gaskets or other suitable means ordinarily employed for such purposes.

Having thus described the invention, what I believe to be new, and desire to secure by Letters Patent, and what I therefore claim, is—

1. In an apparatus for artificially curing 65 tobacco, the combination with an apartment for the tobacco, of devices for simultaneously spraying the tobacco and maintaining the

temperature of the apartment at a low degree, said devices including a steam-spray pipe discharging into the apartment and a refrigerant-pipe located in the apartment and independent of said spray-pipe, substantially as described. 70

2. In a means for artificially curing tobacco, the combination of an air-tight apartment for the tobacco, a spray-pipe in said apartment, pipes for the circulation of heating and refrigerating agents through said apartment, and means for supplying spraying, heating and refrigerating agents to said 80 pipes. 75

3. In a means for artificially curing tobacco, the combination with an air-tight apartment having racks from which to suspend the tobacco-leaves, of a spraying-pipe, 85 pipes for the circulation of heating and refrigerating agents, all of said pipes being located in said apartment, and means for supplying spraying, heating and refrigerating agents to said pipes. 90

4. In an apparatus for curing tobacco artificially, the combination of a receptacle for containing the tobacco undergoing treatment, and means for circulating heating and refrigerating agents within said receptacle and 95 for spraying the tobacco in said receptacle, substantially as described, whereby the tobacco is sprayed, refrigerated and heated in the one receptacle, as specified. 90

5. In an apparatus for artificially curing 100 tobacco, the combination with an apartment for the tobacco to be treated, of a valved pipe leading from a source of chilled-brine supply, a valved pipe leading from a source of steam-supply, and a pipe in the apartment 105 having communication with both of the previously-mentioned pipes and common both to chilled brine and steam, as and for the purposes specified. 100

6. In an apparatus for artificially curing 110 tobacco, the combination with an apartment for the tobacco to be treated, of a valved pipe for the supply of a refrigerating agent, a valved pipe for the supply of steam, means for circulating steam and the refrigerating 115 agent through the apartment, and a spray-pipe having a valve-controlled communication with the steam-supply pipe. 110

7. In an apparatus for artificially curing 120 tobacco, the combination with an apartment for the tobacco to be treated, of a valved pipe for the supply of a refrigerating agent, a valved pipe for the supply of steam, a pipe in the apartment having communication with both of said supply-pipes and common to both 125 the steam and the refrigerating agent, and a spray-pipe in said apartment, having a valve-controlled pipe for supplying it with steam from the steam-supply pipe. 120

8. In an apparatus for artificially curing 130 tobacco, the combination with an apartment for the tobacco to be treated, of an upper and a lower coil in said apartment, a down-pipe connecting said coils together, a valve for

controlling communication of the upper coil with the lower coil, a valve for controlling communication of the lower coil with the down-pipe, a valved spray-pipe connected 5 with said down-pipe, a valved pipe for refrigerant, discharging into the upper coil, a valved pipe for a heating agent also discharging into said upper coil, and a valved pipe for the spraying agent, connecting the 10 latter supply-pipe with the down-pipe, substantially as described and for the purposes set forth.

9. In an apparatus for artificially curing tobacco, the combination with an apartment 15 for the tobacco to be treated, of a valved pipe for the supply of chilled brine, a valved pipe for the supply of a brine-expelling agent, a valved pipe for the supply of a heating agent, and a pipe in said apartment having communication 20 with the several supply-pipes and common to the several agents supplied thereby.

10. In an apparatus for artificially curing tobacco, the combination with an apartment 25 for the tobacco to be treated, of a valved pipe for the supply of chilled brine, a valved pipe for the supply of a brine-expelling agent, a valved pipe for the supply of steam, a pipe in said apartment having communication with 30 all of said supply-pipes, and a spray-pipe in said apartment having valved communication with the steam-supply pipe.

11. In an apparatus for artificially curing tobacco, the combination with an apartment 35 for the tobacco to be treated, of means for circulating a heating agent and chilled brine through said apartment, said means including a pipe in the apartment through which the heating agent and chilled brine both flow, 40 and means for expelling the brine from said pipe in advance of the supply of the heating agent thereto.

12. In an apparatus for artificially curing tobacco, the combination with an apartment 45 for the tobacco to be treated, of means for successively spraying, refrigerating and heating the tobacco in said receptacle, said means including a steam-supply pipe, and a spray-pipe and a heating-pipe both having valve-controlled communication with said steam-supply pipe, substantially as described.

13. In an apparatus for artificially curing tobacco, the combination with an apartment 55 for the tobacco to be treated, of a valved pipe for the supply of a refrigerant, a valved pipe for the supply of steam, a coil in the apartment having communication with both of said supply-pipes and common to both the refrigerating and heating agents, and a spray-pipe 60 in the apartment having a valved connection with said steam-supply pipe independent of said coil, substantially as described and for the purposes set forth.

14. In an apparatus for artificially curing tobacco, the combination with an apartment 65 for the tobacco to be treated, of a four-way coupling, a pipe for chilled brine, a pipe for

steam and a pipe for a brine-expelling fluid all entering said coupling, said pipes having valves, a coil arranged in said apartment and leading from said coupling, a three-way coupling to which said coil leads, a valved brine-return pipe leading from said three-way coupling, a valved, down-pipe also extending from said three-way coupling, a valved steam-coil 75 communicating with said down-pipe, a valved spray-pipe likewise communicating with said down-pipe, and a valved pipe connecting the steam-supply pipe with said down-pipe, substantially as described and for the purposes 80 set forth.

15. In an apparatus for artificially curing tobacco, the combination with an apartment for the tobacco to be treated, of a pipe in said apartment, means for successively delivering 85 to said pipe chilled brine for refrigerating the tobacco, a brine-expelling fluid, and steam for heating the tobacco, and a steam-spray pipe also located in said apartment.

16. In an apparatus for artificially curing 90 tobacco, the combination with an air-tight apartment having racks from which to suspend the tobacco, and means for successively heating and refrigerating said apartment, said means including a steam-supply pipe and 95 a pipe in the apartment through which steam for heating purposes flows, of a spray-pipe having a valved connection with said steam-supply pipe.

17. In an apparatus for artificially curing 100 tobacco, the combination with an air-tight apartment having racks from which to suspend the tobacco, of a pipe in said apartment, means for successively delivering steam and a refrigerant to said pipe, and a steam- 105 spray pipe having an independent connection with the steam-supply pipe, whereby the refrigerant and the spray may be used at once.

18. In an apparatus for artificially curing tobacco, the combination with an air-tight 110 apartment having racks from which to suspend the tobacco, of a pipe in said apartment, means for successively delivering to said pipe chilled brine for refrigerating the tobacco, a brine-expelling fluid, and steam 115 for heating the tobacco, and a steam-spray pipe also located in the apartment and having a separate valved connection with the steam-supply pipe, substantially as described and for the purposes set forth.

19. In an apparatus for artificially curing tobacco, the combination with an apartment for the tobacco to be treated, and a spray-pipe discharging into said apartment, of pipes 125 in said apartment, having communication with sources of steam and chilled-brine supply and serving to circulate steam and chilled brine through the apartment, substantially as described and for the purposes set forth.

20. In an apparatus for artificially curing 130 tobacco, the combination with an air-tight apartment for the tobacco to be treated, of means for successively spraying, refrigerating, 135 heating and drying the tobacco in

said apartment, and means for creating air-currents in said apartment to expel gases and odors therefrom, substantially as described.

21. In an apparatus for artificially curing tobacco, the combination with an apartment for the tobacco to be treated, a valved pipe leading from a source of chilled-brine supply and a valved pipe leading from a source of steam-supply, of a brine and steam circulating pipe in the apartment having communication with both of said supply-pipes, a valved pipe leading from a source of compressed-air supply and having communication with said pipe in the apartment, and a valved pipe opening into said apartment and having communication with said compressed-air-supply pipe, for discharging compressed air directly into the apartment, substantially as described and for the purposes set forth.

22. The herein-described apartment for containing tobacco to be cured artificially, said apartment having double walls with an insulating-space between said walls, and a door for said apartment consisting of a plurality of layers of material arranged to form within the interior of the door a space for magnesia and a space for dead air, and a layer of magnesia in the first-mentioned space, combined with means for spraying, heating and refrigerating the contents of said apartment.

In testimony whereof I affix my signature in presence of two witnesses.

DAVID J. ETRY.
